RETRACTABLE LANDING GEAR

Gabriel Midboe, Brooklyn, N. Y., assignor to
 General Aviation Corporation, Dundalk, Md.,
 a corporation of Delaware

Application June 28, 1932. Serial No. 619,720

22 Claims. (Cl. 244—2)

This invention relates to improvements in a landing gear designed primarily as a beach gear for a flying boat, but which can also be used as a landing gear for amphibian and land planes.

5 For this purpose there is attached to each wing, on each side of the hull, a strut and landing wheel adapted to be drawn up and housed within or against the body of the wing so that it offers slight or no resistance to flight when not in use.

10 For holding the strut forming the landing gear and the wheel on the free end thereof, there is provided in each wing, means for supporting the landing gear in a retracted position. There is also provided in the hull of the boat means for bringing the landing gear to an operative position and holding it in that position as long as desired during landing or taking off.

It is particularly the object of this invention to provide means for withdrawing the landing 20 apparatus from its seat in the wing, and holding it in body-engaging position and so holding it that it has no lateral movement.

These and other advantages will appear from the following description taken in connection 25 with the drawings.

Referring to the drawings:

Figure 1 is a side elevation of one part of the hull and one wing, in cross section.

30 Figure 2 is a section through one side and the bottom of the hull, showing the mechanism for bringing the landing gear to a substantially vertical position and holding it in this position.

Figure 3 is a cross section through part of the wing, showing the manner in which the landing gear is retracted and held in retracted position.

35 Figure 4 is a transverse section through one side of the hull and a longitudinal section through the operating mechanism for bringing the operating gear into a substantially vertical position.

40 Figure 5 is a view showing the lefthand end of the operating mechanism shown in Figure 4.

Figure 6 is a view showing the righthand end of the operating drum housed in the wall of the hull.

45 Figure 7 is a top plan view of the gear support and a cross section through the strut supported by the support.

Figure 8 is a section on the line 8—8 of Figure 1. The present landing gear is shown used in 50 connection with a flying boat, which has a hull having sides 1 and a bottom 2. Extending from each side of the hull is a wing 3. To the front spar 4 of each wing, adjacent the side of the boat hull, is a U-shaped bracket 6 attached to the spar by means of bolts 7.

Transverse of the wings and suitably attached to the front spar 4 and the rear spar are ribs 5. On the lower end of each U-shaped bracket is a loop 8 adapted to support pivotally the upper end of a semi-circular strut 9 by means of ears 10, 60 one at each end of the loop. For holding these ears in engagement with the loop a bolt 11 is provided. The front part of the semi-circular strut is indicated by the numeral 12, while the flat rear part is indicated by the numeral 13. 65

The lower end of each strut has on each side, at the rear, a flat, triangular plate 14 for supporting therebetween a wheel 15 on an axle 16 extending through the plates 14. In the front part, near the lower end of each strut, is a socket with a 70 cone-shaped pin 17 therein adapted to receive a tube 18 suitably attached to a support 19 pivoted to one side of the hull at different points. The rear pivot of the support is indicated by the numeral 20 while the front pivot is indicated by 75 the numeral 21. The front pivot is in the form of a short shaft 21a suitably supported by the hull, and a bracket 21b extending inwardly from the hull.

In the side of the boat hull there is a casing or 80 cavity 22, which forms a seat for the support 19 when not in use. This casing or cavity so seats the support that when the plane is in flight no resistance is offered by the support to the air. The rear wall of the casing is indicated by the 85 numeral 23 and is suitably attached to the wall of the hull by any desired means.

Supported by the hull immediately above the casing 22 is a casing or housing 24, which is cylindrical in shape and has on one end a flange 90 25 into which is fitted a sleeve 26. This sleeve 26 has on its outer end a flange 27. Through the flanges 25 and 27, the upper part of the wall 23 and the side 1 of the hull extend rivets 28 for holding these parts assembled, in the 95 manner shown in Figure 4.

Extending downwardly from the housing 24 is an extension 29 attached to the hull of the boat by means of rivets 30. This extension has a 100 passageway 31 leading from the casing 22 into the housing 24, through which a cable 45, later to be described, passes. On the other end of the housing 24 from the flange 25 is a cap 32. This cap is held on this end of the housing by means of flanges 33 and bolts 34 passing through 105 the flanges.

Extending from the end of the cap is a sleeve 35, which has threaded on the end thereof a cap 36, containing a packing 36a. Extending through the cap 36 and the sleeve 35 into the 110

housing 24 is a shaft 37, which has on one end a crank 38 for rotating the shaft. On the other end of this shaft is a hollow drum 39, which has on its periphery a spiral groove 40. This 5 groove is adapted to seat a cable, and also adapted to engage a similar groove on the inside of the sleeve 26 so that as this drum rotates it will move into or out of the housing. By means of this connection a watertight fit is provided 10 so that water may not pass between these parts into the interior of the hull.

In the inner end of the housing and integral therewith is a head 41, which has attached thereto by means of a bolt 43 a flange 42. This flange 15 is formed integral with the shaft 37 so that the flange and the shaft may be removed from the head by removing the bolts 43. When the shaft rotates the hollow drum 39 is caused to rotate and move longitudinally into or out of the housing by means of the spiral groove 40.

Near the center of the shaft, at a point midway between the ends thereof, is a second flange 44, to which one end of a cable 45 is attached. The other end of this cable is attached to some 25 suitable part of the support 19 for drawing it into the casing 22 when not in use. This cable 45 extends through the passageway 31 and is adapted to be wound around the shaft 37 for properly housing the support.

30 Extending from one end of shaft 21a is an arm 46, which has attached thereto one end of a rubber cable or strap 47, the other end of which strap is anchored at a point 48 to the side of the hull. This cable is guided by means of 35 guides 49.

Within the drum 39 is one end of a cable 50 attached to the shaft 37 by an attaching means 51. This cable extends through a suitable opening in the outer end of the drum and passes over 40 a pulley 52 suitably attached to some part of the hull. The other end of this cable is attached at the point 53 to the lower end of the strut 9. This cable and drum are used for bringing the 45 strut to a vertical position, as shown in Figure 1. The outer end of the drum is closed by means of a disc 54, suitably attached to flanges on the drum provided for that purpose.

This disc extends beyond the drum on all 50 parts of its periphery forming a flange 55 for the purpose of guiding the cable into the spiral groove on the drum at the beginning of the rotation of the drum.

Suitably attached to the lower end of the strut 55 opposite the point 53 is a cable 56. This cable extends upwardly from the strut and over a pulley 57 supported by means of a swinging frame 58 supported pivotally on a bracket 59 attached to some suitable part of the wing of the plane. After the cable passes over the pulley 57 it is 60 guided by means of a guide tube 60 to another pulley 61 supported suitably by some part of the hull frame. This cable extends downwardly from the pulley 61 and may be gripped by the hand of an individual for hoisting or elevating the landing gear so that it will be properly seated in a cavity 66 provided for that purpose in the wing.

When the landing gear is in a retracted position, it is held in this position by means of a 70 hook 62 located on a shaft 63, supported suitably in some part of the wing and the hull. On one end of this shaft is an operating handle 64, while on the other end is the hook 62 adapted to engage a catch 65 attached to some suitable 75 part of the strut structure.

In order to hold the strut in operative position, as shown in Figure 1, there is provided a loop 67 to engage the crank 38 to prevent the reverse rotation of the drum. When the landing gear is in a housed position and supported by means of the hook 62, and it is desired to lower the gear, the hook is removed from the catch 65 by means of the handle 64. The gear then, including the strut 9, is free to move downwardly, but the drag of the water, due to the plane passing through it, makes it necessary to provide some means for bringing the strut to a landing position. This is done through the cable 56 attached at one end to the point 53 at the lower end of the strut, and at its other end to the drum 39.

The drum at this time is seated within the housing 24. The cable 45 is wound around the shaft 37. As the drum is rotated through the crank 38, the cable 50 is caused to be wound in the spiral groove. At the same time the drum is forced out of the housing and the cable 45 is unwound from the shaft. This operation continues until the cable 50 is sufficiently wound around the drum 39 so that the strut assumes the 100 position shown in Figure 1, with the cable 45 sufficiently unwound to permit the support 19 to assume a substantially horizontal position, as shown in Figures 1 and 4. In this position the support is out of its casing and the tube 18 projects into the socket, with the pin 17 projecting into the tube.

In order to securely hold the strut in the position shown in Figure 1, it is necessary that the loop 67 be thrown over the crank 38 to prevent the 110 back rotation of the drum. When it is desired to retract the landing gear the loop 67 is removed from the crank and the cable 56 is gripped by the hand and pulled for the purpose of raising the landing gear. When the landing gear is fully 115 retracted the hook 62 engages the catch 65 for supporting the landing gear.

It is desired to comprehend within this invention such modifications as may be embraced with the claims and the scope of the invention.

Having thus fully described the invention, what is claimed as new and desired to be secured by Letters Patent, is:

1. In a landing gear, in combination with an airplane having a wing, a strut pivoted at one end to the wing, the front of said strut being streamlined and the back face flat, and means for swinging the strut up against the wing with the flat side engaging the under side of the wing.

2. In an airplane, a fuselage, a wing having a 130 wheel-receiving socket, and a strut pivoted at one end to the wing and having at its other end a wheel adapted to fit in the socket, said strut having a stream lined front edge and a flat back face to engage the wing when the wheel is in the 135 socket.

3. In a landing gear, in combination with an airplane having a hull, a strut pivoted one end to swing along one side of the hull, and means pivoted on the hull to support the strut when in a substantially vertical position, said means consisting of a support having at its free end a tube adapted to fit in a socket in the strut, and a pin on the strut in the socket to fit in the tube.

4. In a landing gear, in combination with an 145 airplane having a hull and a wing extending from one side, a strut pivoted at one end to the wing for swinging along one side of the hull, means pivoted on the hull to support the strut in a substantially vertical position, and a common means 150

- for moving the strut and said means about their pivots.
5. In a landing gear, in combination with an airplane having a hull and a wing extending therefrom, a strut pivoted at one end to the wing for swinging along the hull, a support pivoted to the hull for engaging the strut to support it in a substantially vertical position, and a common means to move the strut and the support on their pivots, said means including a shaft with a drum thereon, a housing for the drum and means on rotation of the shaft and drum to cause the drum to move into or out of the housing.
10. In a landing gear, in combination with an airplane having a hull and a wing, said hull having a housing, a strut pivoted at one end to the wing, means to hold the strut against the under side of the wing, and means to move the strut to a substantially vertical position, said means including a drum mounted in the housing, a cable attached to the drum and to the strut, means to rotate the drum and cooperating means on the housing and the drum, whereby as the drum rotates it will be moved out of the housing or drawn 25 into the housing and the cable wound about the drum or let off.
15. In a landing gear, in combination with an airplane, a landing strut therefor, means to bring the strut into landing position, a pivoted support 30 for the strut in landing position, and means connected to the strut and the support operable by rotation in one direction to raise the support and operable by rotation in another direction to bring the strut to landing position and release the support so it can move to strut-supporting position.
20. In a landing gear, in combination with an airplane, a landing strut therefor, means to bring the strut into landing position, a pivoted support 35 for the strut in landing position, means connected to the strut and the support operable by rotation in one direction to raise the support and operable by rotation in another direction to bring the strut to landing position and release the support so it can move to strut-supporting position, and 40 means when the support is released to bring it to strut-supporting position.
25. In a landing gear, in combination with an airplane, a landing strut therefor, means to bring the strut into landing position, a pivoted support 45 for supporting the strut when in landing position, means connected to the strut and the support operable by rotation in one direction to raise the support to a vertical position and operable by rotation in another direction to bring the strut to landing position and release the support, 50 means to automatically bring the released support to strut-supporting position, and means to bring the strut out of landing position when it is released.
30. 10. In a landing gear for airplanes, a hull, a landing strut pivotally supported with relation to the hull, a support for the strut pivoted to the hull, means tending to hold the support in strut-supporting position, and a rotatable member in 55 the hull adapted at one operation to move the support out of strut-supporting position and at another operation to release the support and bring the strut into landing position against the support.
35. 11. In a landing gear, a movable strut member, means to move the strut into operative position for landing purposes, a support for said strut when in operative position, and means tending to hold the support in strut-supporting position, said first-named means being connected to the support 60 and adapted to move the support out of strut-supporting position.
40. 12. In a landing gear, a pivoted strut, a pivoted support for the strut, and means operatively connected to the strut and the support for moving them, said means consisting of a drum, a shaft on the drum, means for rotating the shaft and the drum, and a support for the shaft and drum so engaging the drum that the rotation of the drum will cause the drum to move longitudinally.
45. 13. In a landing gear, an operating mechanism therefor comprising, in combination with a hull having therein a hole, a cylindrical housing having on one end a flange fitting against the inside of the hull around the hole, a sleeve fitting in the housing and having a flange engaging the outside of the hull, means to fasten the flanges together and to the hull, a drum having on its periphery a spiral groove and at one end a flange, and means in the sleeve engaging the groove so that when the drum is rotated it will move longitudinally into and out of the housing.
50. 14. In a landing gear, an operating mechanism therefor comprising, in combination with a hull having a hole therein, a cylindrical housing attached at one end to the hull within the hole, the end of the housing at the hull being open, a drum having a spiral groove around its periphery in the open end of the housing, means in the housing engaging the drum in the groove so that when the drum rotates it will move into and out of the housing, a shaft extending through the other end of the housing and supported thereby, means for attaching one end of the shaft to the drum, and means for rotating the shaft.
55. 15. In a landing gear, an operating mechanism therefor comprising, in combination with a hull having a hole therein, a cylindrical housing attached at one end to the hull within the hole, the end of the housing at the hull being open, a drum having a spiral groove around its periphery in the open end of the housing, means in the housing engaging the drum in the groove so that when the drum rotates it will move into and out of the housing, a shaft extending through the other end of the housing and supported thereby, 60 means for attaching one end of the shaft to the drum, means for rotating the shaft, and a pair of cables attached to the shaft, one cable extending through the outer end of the drum.
65. 16. In a landing gear, an operative mechanism therefor comprising, in combination with a hull having a recess therein, a water-tight housing attached to the inside of the hull around the recess, and a drum in the housing.
70. 17. In a landing gear, an operative mechanism therefor comprising, in combination with a hull having a hole therein, a water-tight housing attached to the inside of the hull around the hole, a drum in the housing, and co-operating means on the drum and housing whereby when the drum rotates it will move longitudinally.
75. 18. In a landing gear, in combination with an airplane having a wing, a strut pivoted at one end to the wing, the front side of the strut being arcuate and the back side flat, means to swing the strut up against the wing with the flat side engaging the under side of the wing, and means to lock the strut against the wing, said means including a catch member on the strut and a swinging hook to engage the catch member.
80. 19. In a landing gear, in combination with an airplane having a hull and a wing extending therefrom, a strut pivoted at one end to the wing and having on its other end a wheel, said strut 85
85. 100. 105. 110. 115. 120. 125. 130. 135. 140. 145. 150.

having its front side arcuate and gradually increasing in size from the pivot end to the wheel and its back side flat, means to swing the strut up against the wing with the flat side engaging 5 the underside of the wing, and means to lock the strut against the wing, said means consisting of a latch member on the strut and a shaft supported by the hull, said shaft having on one end a hook to engage the latch member and on 10 the other end a handle for operating the hook.

20. In combination in an airplane of a body, a wing, a wheel strut having a wheel on one end pivoted to the wing adapted to swing parallel with the side of the body, and a locking yoke pivoted on the side of the body adapted to engage with 15 the strut when in vertical landing position.

21. In combination in an airplane of a body, a wing, a wheel strut having a wheel on one end pivoted to the wing adapted to swing parallel with the side of the body, a locking yoke pivoted 20 on the side of the body adapted to engage with the strut when in vertical landing position, and

means inside of said body connected to said yoke and to the forward end of said strut, whereby as said strut is moved into vertical position by said means the yoke is released for engaging the strut and when the yoke is withdrawn from the strut the means for moving the strut into vertical position 80 is slackened off.

22. In combination in an airplane of a body, a wing, a wheel strut having a wheel on one end pivoted to the wing adapted to swing parallel with the side of the body, a locking yoke pivoted on the side of the body adapted to engage with the strut when in vertical landing position, means inside of said body connected to said yoke and to the forward end of said strut, whereby as said 85 strut is moved into vertical position by said means the yoke is released for engaging the strut and when the yoke is withdrawn from the strut the means for moving the strut into vertical position 90 is slackened off, and means for moving the strut into a horizontal position against the wing.
